UNITED STATES PATENT OFFICE.

ALBERT GEORG KOECHLIN, OF BASEL, SWITZERLAND, ASSIGNOR, BY MESNE ASSIGNMENTS, TO DRAPER COMPANY, OF HOPEDALE, MASSACHUSETTS, A CORPORATION OF MAINE.

AUTOMATIC WEFT-BOBBIN-EXCHANGING DEVICE FOR LOOMS.

1,074,629.

Specification of Letters Patent.

Patented Oct. 7, 1913.

Application filed November 1, 1911. Serial No. 657,996.

To all whom it may concern:

Be it known that I, ALBERT GEORG KOECHLIN, a citizen of the Swiss Republic, and resident of Basel, Switzerland, have invented new and useful Improvements in Automatic Weft-Bobbin-Exchanging Devices for Looms, of which the following is a full, clear, and exact specification.

The present invention relates to improvements in automatic weft bobbin exchanging devices for looms of the kind described in my United States Letters Patent application Ser. No. 652954, filed October 5, 1911. In this application an improvement was described as applied to automatic weft bobbin exchanging devices for looms in which the weft spool or bobbin magazine generally consisted of a casing or box without any movable inner partition wall, which was provided with a retaining wedge-shaped member placed on the inner side of the casing near the lower bobbin exit opening for the purpose of allowing the single bobbins to pass more easily through the opening and to separate the layers of bobbins one from the other. Also the floor of the casing was provided with a guide for the bobbins of the lowest layer, a transferring guide channel being arranged contiguous to the bobbin exit opening of the casing and lying somewhat lower than it. It has now been found that in such an arrangement the inner retaining wedge-shaped member of the bobbin magazine may be replaced by outer movable retaining means which are so arranged with regard to the bobbin exit opening of the casing and the said transferring guide channel and are so limited in their outward movement that they only allow one row of bobbins to slide on to the transferring guide channel under the pressure of the supply of bobbins stored in the magazine at the same time holding back the other bobbins. In this arrangement the side of the bobbin magazine itself is of extreme simplicity and also the transferring guide channel need not be arranged lower than the floor of the magazine where it joins the latter at the bobbin exit opening.

The retaining means preferably consist of two movably (pendulum or slidable) arranged retaining members which each act as a retaining stop for the second and third lowest row of bobbins and are controlled

by weight or spring action so that they are unable to pass beyond a predetermined end position under the pressure of the bobbins. The retaining means could also consist of a single movably arranged retaining member the outside position of which is limited by an adjustable stop. Any suitable retaining members such as pivoted flaps, loops, weight rollers or the like, slidably mounted pressure members or the like may be used.

Three constructions of the apparatus according to the present invention are illustrated on the accompanying drawing, in which:

Figure 1 is a sectional elevation of the preferred construction. Fig. 2 is a sectional elevation of a second construction. Figs. 3 and 4 are detail views of the third constructional form.

In the drawings, *a* is the magazine chamber for receiving a plurality of superposed layers of weft spools or bobbins, having the form of a box without any inner partition wall, which is provided at its front side with a lower bobbin exit opening *b* and has a guide rail *d* arranged on the slightly inclined base of the box for the guiding of the bobbins of the lowest row of bobbins lying within it. A bobbin transferring guide channel *f* is directly contiguous to the opening *b* and conveys the bobbins one after the other directly to the usual transference *g*.

In Fig. 1 two retaining flaps *i* and *i'* are hung on the outside of the bobbin casing *a* in the manner of pendulums and owing to their unequal length in their normal position, form retaining stops for the second and third lowest row of bobbins, while they leave free the lowermost row of bobbins, thus allowing the latter to pass on to the transferring guide channel *f*. Owing to their own weight they take up the normal position shown in the drawings and their weight is so calculated that their outward oscillating movement is limited only by the action of gravity, without any special stops, although in some cases additional stop means may also be employed. Should for any reason the inner shorter flap *i* be pressed out of its normal position owing to the pressure of the bobbins in the magazine chamber, then it will finally abut against the outer flap *i'* and then the pressure of the

bobbins will be unable to overcome the combined weight action of both flaps.

In the constructional form according to Fig. 2 instead of two flaps being arranged 5 pivotally about the same axis, two weight rollers m , m^1 are freely suspended from two different axes and form in the like manner retaining stops for the second and third lowest row of bobbins. In the constructional form shown in Figs. 3 and 4 a single suspended retaining flap n is used, the outer limit position which it can take up under excessive bobbin pressure in the magazine being limited by an adjustable stop o . The 10 latter consists of a set screw provided with a conically shaped projecting head so that the outer limit to which the flap can move may be adjusted by screwing in or out this stop o . When the stop o is completely 15 screwed out the flap n is free.

What I claim is:

1. In an automatic weft bobbin exchanging device for looms of the kind above referred to, the arrangement of a bobbin 25 magazine in form of a substantially rectangular box without any inner partition wall for receiving a plurality of superposed layers of bobbins, said box having a slightly inclined base with a guide-rail thereon for the bobbins of the lowest layer 30 and being provided with a lower bobbin exit opening, a movable transerrer for transferring the bobbins into the working shuttle, a guide-channel for conveying the bobbins 35 from the box directly to said transerrer, and a movable retaining device outside the box for retaining the superposed bobbin layers with the exception of the lowest one which is entirely free to pass onto the transferring guide-channel under the pressure 40 of the supply of bobbins in the magazine, substantially as described.
2. In an automatic weft bobbin exchanging device for looms of the kind above referred to, the arrangement of a bobbin 45 magazine in form of a box without any inner

partition wall for receiving a plurality of superposed layers of bobbins, said box having a slightly inclined base with a guide-rail thereon or the bobbins of the lowest 50 layer and being provided with a lower bobbin exit opening, a movable transerrer for transferring the bobbins into the working shuttle, a guide-channel for conveying the bobbins from the box directly to said transerrer, and two movable retaining members 55 outside the box so arranged with regard to said opening and guide-channel as to form a stop respectively for the second and third lowest row of bobbins of the supply of 60 bobbins, while they leave free the lowermost row of bobbins, substantially as described.

3. In an automatic weft bobbin exchanging device for looms of the kind above referred to, the arrangement of a bobbin 65 magazine in form of a box without any inner partition wall for receiving a plurality of superposed layers of bobbins, said box having a slightly inclined base with a guide-rail thereon for the bobbins of the lowest layer 70 and being provided with a lower bobbin exit opening, a movable transerrer for transferring the bobbins into the working shuttle, a guide-channel for conveying the bobbins from the box directly to said transerrer, and 75 two hinged retaining members outside the box, of different operative length and of such a weight as to be limited in their outward oscillating movement, said retaining members constituting a stop respectively for the 80 second and third lowest row of bobbins of the supply of bobbins while leaving free the lowermost row of bobbins, substantially as described.

In witness whereof I have hereunto signed 85 my name this 21st day of October, 1911, in the presence of two subscribing witnesses.

ALBERT GEORG KOEHLIN.
